MAT

Albert T. Ecklund, Jamestown, N. Y., assignor of
one-half to Wallace C. Price, Jamestown, N. Y.

Application February 24, 1934, Serial No. 712,785

9 Claims. (Cl. 20—78)

This invention relates to an improvement in mats and more particularly to that class of mats which are fabricated from pre-cut strips of suitable wear resistant material.

5 Mats of the class to which this invention is related are subjected to constant and hard usage and must therefore be produced from strips of suitable wear resistant material. These strips must be securely bound or fastened together so 10 that they will not spread apart or tear loose during use.

The preferred embodiment of the invention discloses several modifications of a mat assembled from a plurality of longitudinally extending strips held together in varied relative position through the use of transversely arranged binders. These strips may be made to abut each other at the location of the binders, or may be spaced apart by suitable washers or return folded portions of 20 the strips. The particular arrangement of the strips is intended to provide lengthwise tension as well as a design of attractive appearance. To obtain this tension, certain of the strips are somewhat elastic and, when assembled under tension, 25 cause all of the strips of the mat to be more closely related than is possible through the use of transverse binders alone.

One of the objects of the invention lies in the provision of a mat formed from a plurality of strips, certain of which are assembled under lengthwise tension.

Another object of the invention lies in the provision of a mat formed from strips of substantially uniform size which, when assembled, present an 35 uneven tread surface.

A further object of the invention lies in the provision of folds or loops to produce an attractive finish to the mat ends.

Other and further objects of the invention will 40 be more fully understood from a consideration of the following specification which is taken in conjunction with the accompanying drawing and in which,

Figure 1 is a fragmentary plan view, partly in 45 section, of one modification of the invention showing two methods of finishing the ends of the mat;

Figure 2 is an enlarged vertical sectional view 50 through one of the binders, being taken substantially on the line 2—2 of Figure 1;

Figure 3 is another enlarged vertical sectional view 55 taken substantially on the line 3—3 of Figure 1;

Figure 4 is a plan view of a modification of the structure shown in Figure 1; and

55 Figure 5 is an enlarged vertical sectional view of the modified mat, taken substantially on the line 5—5 of Figure 4.

Referring to Figure 1 of the drawing, one modification of the invention, generally indicated by 60 the reference numeral 10, is shown to be com-

prised of a plurality of longitudinally extending strips of similar or slightly varying length. For a clearer understanding of the invention, the straight line strips are indicated by the numeral 11 and are spaced apart by one or more curved strips 12. Each of the strips 11 and 12 are cut as near as practicable of uniform width and thickness. Transverse openings 14 and 15 are made in the strips 11 and 12. These openings are spaced apart a suitable distance and serve to receive the binder wires 16 therethrough. It is to be understood that, prior to assembly, strips 12 are straight and that the openings 15 therein are spaced apart a distance equal to that of the spacing of the openings 14 in strips 11. Strips 11 may be formed from any suitable wear resistant material having little or no elasticity. Strips 12, however, are preferably formed from a somewhat elastic material which permits stretching said strips during assembly of the mat to produce the 20 regular curved portions shown in the drawing. The strips 12 must, of necessity, be stretched to cause the openings 15 therein to register with the wires 16 which project through openings 14 of strips 11. In order to limit the tension of strips 25 12, straight strips 11 may be alternated throughout the mat. To conceal that portion of the binder wires 16 which is exposed between the strips 11 and 12, suitable washers 17 are provided. These washers constitute spacers between the longitudinally extending strips and facilitate slight 30 rearrangement of the strips for the purpose of modifying the design of the mat.

For convenience, the binder wire 16 is generally U-shaped, the closed end 19 being fitted with a 35 plate 20 which forms a suitable abutment against the outer face of the marginal strip 11. When the mat is completely assembled the free ends 22 of the wire 16 are projected through suitable openings 23 in a plate 24 which lies against the 40 other marginal strip 11. Two additional openings 25 are made adjacent the center of the plate 24 and receive the return bent ends 27. These ends may be embedded or anchored in the adjacent portion of the strip 11.

Figure 1 of the drawing shows all of the strips at one end of the mat to terminate adjacent the endmost binder wire 16. The ends of the strips 11 and 12 are rounded or otherwise made to conform to the contour of the washers 17 for the purpose 50 of providing a plain marginal end to the mat. The other end of the mat shows the strips 12 to be what may be termed one binder section longer than the strips 11 to form extensions 29. These extensions have one additional opening 15 therein which facilitates their being folded back upon themselves to be engaged by the endmost wire 16. Since the material from which the strips are made is both heavy and very rugged, it is found preferable to space the end of the exten- 55 60

sions 29 one or more washer widths although this arrangement may be varied according to the designer of the mat and the materials which are being used. When the extensions are folded back, 5 as above described, loops or scallops 30 are formed which materially add to the attractiveness of the marginal ends of the mat. The provision of the extensions 29 also serves the purpose, in particularly long or heavy mats, of providing means for doubly securing or anchoring the ends of the tension strips 12.

The modification in Figures 4 and 5 of the drawing shows a mat 33 which is comprised of strips 34 and 35. In this modification the straight strips 34 are spaced apart by two of the curved strips 35, said latter strips being in abutment with each other at the location of alternate binders. At this point sufficient space is provided for two washers 36 whereas at the farther spacing of 20 the strips 35, four of the washers 36 are interposed. The mat 33 is held together by the binder wires 38 which, being substantially identical with the wires 16 in appearance and use, will not further be described. The ends of the strips 35 are 25 formed with extensions 39 similar to the extensions 29. These extensions are folded inwardly and abut each other, being so held by the tension of the material and one or more washers 36. In this instance, the marginal ends of the mat are 30 provided with pairs of loops or scallops between which the ends of the straight strips 34 are located. This modification also requires fewer 35 number of straight strips than does the disclosure in Figure 1.

35 Due to the fact that curved strips 12 and 35 are assembled under lengthwise tension, the cross section of these strips is less than the cross section of strips 11 or 34. Thus the mats on their upper and lower surfaces present slightly raised 40 scuff ribs which are formed by the projecting edges of straight strips 11 or 34. Changing the number of washers 17 or 36 not only facilitates 45 change in design but also a change in the lengthwise tension of the mat. That is to say, elimination of one washer on each binder wire 16 between any two adjacent strips 11 decreases the space therebetween and permits assembly of the strip 12 in more flattened curves than is shown in Figure 1 of the drawing. The straighter the strip 50 12, the less the material thereof is stretched for the purpose of causing the openings 15 therein to register with the wires 16.

Although applicant has shown only two modifications or designs of his invention, in which 55 are embodied means for binding together a longitudinally extending strip mat, means for producing endwise tension, and further means for producing scuff ribs, it will be understood that other modifications or additions to these features are 60 contemplated in so far as they may be included in the spirit and scope of the invention as defined by the hereunto annexed claims.

Having thus set forth my invention what I 65 claim as new and for which I desire protection by Letters Patent is:—

70 1. A mat of the class described comprising a pair of mat length marginal strips, a plurality of intermediate straight and curved strips between said marginal strips, transversely arranged binder means securing all of said strips, said curved strips being under lengthwise tension whereby to

cause all of said strips to have relative pressure contact.

2. A mat of the class described comprising a plurality of generally longitudinally extending strips, means for securing said strips in pressure contact transversely of their length, certain of said strips being elastic, said certain strips being secured under lengthwise tension by said means and exert a pressure contrary to the pressure of said means. 10

3. A mat of the class described comprising a plurality of generally longitudinally extending strips, means for securing said strips together, all of said strips being normally substantially uniform in cross section, certain of said strips being 15 somewhat elastic, said certain strips being extended and assembled under lengthwise tension, said certain strips, when assembled, having a lesser cross section than the other of said strips whereby to provide scuff portions on said mat. 20

4. A mat of the class described comprising a plurality of generally longitudinally extending strips, all of said strips being normally substantially uniform in cross section, certain of said strips being elastic, said certain strips, when assembled under lengthwise tension, having a lesser 25 cross section than the other of said strips whereby to form scuff portions of said other strips.

5. A mat of the class described comprising a pair of mat length marginal strips, a plurality of 30 intermediate straight and curved strips between said marginal strips, said curved strips having some elasticity, binder means for securing all of said strips together, said curved strips being under lengthwise tension and serving to exert a 35 pressure contact opposed to said binder means whereby to provide a substantially non-separable strip mat.

6. A mat of the class described comprising a plurality of mat length straight and curved 40 strips, said curved strips being alternated with said straight strips throughout the width of said mat, spacer means interposed between certain of said strips, said spacer means serving to maintain the desired curvature of said curved strips, 45 and binder means for securing all of said strips, said binder means serving to mount said spacer means.

7. A mat of the class described comprising a plurality of mat length strips, certain of said 50 strips being elastic, means for producing lengthwise tension in said certain strips, said means being variable to vary the lengthwise tension of said mat, and further means securing all of said strips together. 55

8. A mat of the class described comprising a pair of mat length marginal strips, a plurality of intermediate straight and curved strips between said marginal strips, means securing said strips together, said curved strips being under 60 lengthwise tension whereby to cause all of said strips to have relative pressure contact.

9. A mat of the class described comprising a plurality of generally longitudinally extending strips, means for securing said strips laterally 65 under transverse pressure, certain of said strips being elastic, said certain strips being secured under lengthwise tension by said means and exerting a pressure contrary to the pressure of said means. 70
